CLAIM

The ornamental design for a printer, as shown.

DESCRIPTION

FIG. 1 is a side elevational view of a printer showing our new design;

FIG. 2 is a top plan view of the printer;

FIG. 3 is a front elevational view of the printer;

FIG. 4 is a fragmentary sectional view taken along the line 4—4 of FIG. 3;

FIG. 5 is an opposite side elevational view of the printer;

FIG. 6 is a rear elevational view of the printer; and

FIG. 7 is a bottom plan view of the printer.
